UNITED STATES PATENT OFFICE

108,495

DESIGN FOR A FORK BLADE

Clarence R. T. Hess, Prairie View, Ill.

Application March 24, 1937, Serial No. 68,385

Term of patent 14 years

To all whom it may concern:

Be it known that I, Clarence R. T. Hess, a citizen of the United States, residing at Prairie View, in the county of Lake and State of Illinois, have invented a new, original, and ornamental Design for a Fork Blade, of which the following is a specification, reference being had to the accompanying drawing, forming part thereof.

Fig. 1 is a plan view of a fork blade showing my new design;

Fig. 2 is a side elevational view thereof;
Fig. 3 is a perspective view thereof; and
Fig. 4 is a sectional view taken on line 4—4
of Fig. 1.

I claim:

The ornamental design for a fork blade, substantially as shown.

CLARENCE R. T. HESS.
